The ornamental design for an wheel adapter fitting for coolers, as shown and described.

DESCRIPTION

FIG. 1 is a front elevational showing my new wheel adapter fitting for coolers in use upon a cooler, with dashed lines showing environment;

FIG. 2 is a frontal, upper isometric view showing my new design;

FIG. 3 is a lower, rear isometric view thereof;

FIG. 4 is an upper, rear isometric view thereof;

FIG. 5 is a right side elevational view thereof;

FIG. 6 is rear plan view thereof;

FIG. 7 is right side elevational view thereof;

FIG. 8 is left side elevational view thereof;

FIG. 9 is a top plan view thereof; and,

FIG. 10 is a bottom plan view thereof.

The broken lines in the drawing depict environmental subject matter only and form no part of the claimed design.
